UNITED STATES PATENT OFFICE.

JOHN STRAND, OF MANKATO, KANSAS.

CORN-HARVESTER.

SPECIFICATION forming part of Letters Patent No. 709,424, dated September 16, 1902.

Application filed August 2, 1901. Serial No. 70,633. (No model.)

To all whom it may concern:

Be it known that I, JOHN STRAND, a citizen of the United States, and a resident of Mankato, in the county of Jewell and State of 5 Kansas, have invented a new and Improved Corn-Harvester, of which the following is a full, clear, and exact description.

The purpose of this invention is to provide an implement which when operated in a corn-field will receive the standing corn, snap the ears from the stalks, and cut the husks of the ears as they leave the snapping device, and also to so construct and group the said parts that they can be used effectually in connection with husking devices including elevators.

A further purpose of the invention is to construct an implement of the character above described in a simple, durable, and economic manner and so that the standing corn will be 20 automatically guided to the snapping device, and whereby the stalks of corn, should they incline toward the ground, will be lifted and conducted to the aforesaid snapping devices.

The invention consists in the novel construction and combination of the several parts, as will be hereinafter fully set forth, and pointed out in the claims.

Reference is to be had to the accompanying drawings, forming a part of this specification, 30 in which similar characters of reference indicate corresponding parts in all the figures.

Figure 1 is a side elevation of the improved implement. Fig. 2 is a vertical longitudinal central section drawn on an enlarged scale. 35 Fig. 3 is a plan view of the implement; and Fig. 4 is a rear elevation of the snapping device, parts being broken away, and a perspective view of the husking-rollers, illustrating their position relative to the snapping 40 device.

The main frame A is pivotally mounted upon an axle 10, which main frame consists of side bars 11 and a rear extension 12, suitably braced, and at the central portion of the 45 rear end of the main frame A a caster-wheel 14 is located, the shank 15 whereof extends up through a platform 13 on the main frame and is provided with an arm 16 at its top, so that the pilot or caster wheel 14 may be 50 turned in a suitable direction to guide the machine. A shorter and auxiliary frame A' is pivoted on the axle 10, and this shorter or

auxiliary frame consists of side bars 11^a, connected at the back by a cross-bar 12^a. An intermediate cross-bar 13^a is also employed to 55 connect the side members of the auxiliary frame A'. Suitable supporting-wheels 14^a are carried by the axle 10. The auxiliary frame A' is also preferably provided with a central longitudinal beam 15^a, having a flooring 16^a connected therewith or formed integral with the lower side portions of the said beam; but the said beam 15^a may be omitted, if desired.

Braces 17 are carried from the forward portion of the auxiliary frame A', one brace being located at each side of the center of the said auxiliary frame, and these braces 17 have a forward and downward inclination, as is best shown in Fig. 2. These braces serve to 70 support the lower ends of semicircular casings or housings 18, the opposing faces of which casings or housings are open, as is shown in Fig. 4. The rear ends of the housings or casings 18 are supported by standards 19, which 75 are also connected at their lower ends with the auxiliary frame A'.

The rear portions of the housings or casings 18 are closed by suitable partitions 20, as shown in Figs. 1 and 2, and the upper rear 80 portions of the housings are braced by bars 21, which extend downwardly and rearwardly to an engagement with brackets 22, secured upon the rear portion of the auxiliary frame A'. At the forward end of each housing or 85 casing, said forward ends being closed, as is shown in Figs. 2 and 3, triangular guide-fingers 23 are located, having a forward and downward inclination, and these fingers 23 are preferably of skeleton formation, as is 90 particularly shown in Fig. 3, and the inner faces of the fingers are carried from the inner edges of the housings or casings. The said inner faces of the fingers 23 diverge as they extend forward. These fingers are adapted to guide the cornstalks between the casings or housings, and the forward extremities of the fingers are curved laterally in opposite directions to facilitate such guidance. As will be hereinafter described, the auxiliary frame A' may be raised or lowered, so 95 that these fingers may be made to receive between them cornstalks which incline toward the ground as well as standing stalks.

A snapping-roller 24 is located within each casing or housing 18, the trunnions of said snapping-rollers being journaled in the end portions of the housings, and each snapping-roller 24 is longitudinally corrugated or is provided with longitudinal teeth or ribs 25, as is clearly shown in Fig. 3. These snapping-rollers are adapted to revolve in opposite directions. The rear trunnion of each snapping-roller 24 carries a bevel-pinion 26, these pinions being outside of the rear ends of the housings or casings. Bearings 27 are erected upon the upper rear portions of the housings or casings 18, as is shown in Fig. 4, and these bearings journal the ends of the shaft 28, (shown in the same figure,) which shaft carries two bevel-pinions 29. These bevel-pinions mesh with similar pinions 30, located at the upper ends of short vertical shafts 31, mounted to turn at the upper ends of the housings or casings near their inner longitudinal edges, as is also shown in Fig. 4, and each short shaft 31 carries a sprocket-wheel 32, for a purpose to be hereinafter described.

A sprocket-wheel 33 is secured on the shaft 28 between the bevel-pinions 29, and an endless chain belt 34 is passed over this sprocket-wheel 33 and over a sprocket-wheel 35, secured upon a drive-shaft 36, which drive-shaft is journaled in bearings 37, secured to the outer upper end portions of the housings or casings, as is illustrated in Fig. 2. This drive-shaft 36 carries a sprocket-wheel 37^a at each end, and these sprocket-wheels 37^a are connected by chains 38 with large sprocket-wheels 39, secured to the main supporting-wheels 14^a or upon the axle 10.

Chain belts 40 are located over the housings or casings at their inner longitudinal edges. These chain belts 40 may be provided with spurs and are passed over the sprocket-wheels 32 on the upper short vertical shafts 31. The said chain belts 40 are in sections, and motion is communicated to the sections by sprocket-wheels 41, over which the adjacent ends of the sections of the belt pass. The said belts 40 extend to the forward ends of the guide-fingers 23, at which point they are passed over suitable sprocket-wheels 42. These upper endless belts 40 are adapted to engage with the stalks and carry said stalks rearward between the snapping-rollers 24. At all times the housings 18 and snapping-rollers have a downward and forward inclination, and the snapping-rollers are of greater diameter at their rear than at their forward ends, so that the progress of the ears of corn up the said rollers will be more or less retarded. As stated, the snapping-rollers revolve in opposite directions, and as a stalk of corn passes up through the space between these rollers the stems of the ears will be notched and snapped off by the action of the rollers 24 in revolving in a manner to be hereinafter described, since corresponding teeth 25 of the snapping-rollers will simultaneously

be brought upward in the revolution of these rollers and will engage with the stem of the cob, snapping it from the stalk.

The snapping-rollers 24 are revolved by causing bevel-gears 43, located on the drive-shaft 36, to engage with the gears 26 on the upper trunnions of said snapping-rollers, as is shown in Figs. 3 and 4.

When an ear of corn is snapped from the stalk, it will fall on the snapping-rollers and will be carried either to the right or left hand side of the machine within the casing or housing 18, and each casing or housing 18 at its bottom portion is provided with a trough 44. (Shown best in Fig. 3.) In each trough 44 an endless chain or conveyer 45 is mounted to travel longitudinally of the housing or casing, the chain belts being provided with flights 46, placed longitudinally thereof. These endless conveyer-chains 45 pass over sprocket-wheels 47, journaled in the forward lower portions of the housings or casings 18, as is shown in Fig. 2, and they likewise pass over sprocket-wheels 48, secured upon shafts 49, which shafts are journaled in bearings formed at the upper ends of arms 50, extending from the standards 19 at the rear thereof in an upward direction, as is shown in Figs. 1 and 2. These shafts 49 are set in motion by gears 51, secured on the shafts 49, meshing with gears 52, which gears are secured upon a lower shaft 53, journaled in the upper ends of the standards 19, as is shown in Figs. 3 and 4. The shaft 53 is driven from the drive-shaft 36, preferably through the medium of a chain belt 54, which passes over a sprocket-wheel 55, located on the drive-shaft 36, and over a sprocket-wheel 56, secured upon the driven shaft 53.

Two sets of husking-rollers C are located diagonally within the auxiliary frame, the husking-rollers having a downward and rearward inclination, and the forward ends of these husking-rollers are beneath the rear ends of the conveyers 45 at each side of the snapping-rollers. The rear ends of the husking-rollers are of the greatest diameter, so that the ears of corn received thereon will be somewhat retarded in their passage from the forward to the rear ends of the husking-rollers. One roller 57, preferably the outer roller, is provided with longitudinal ribs or serrations, while the opposing or inner roller 58 of each pair of husking-rollers is plain or smooth. The trunnions of the outer husking-rollers 57 are journaled in plates 59, (shown best in Figs. 3 and 4,) which plates are suitably supported upon the auxiliary frame, while the trunnions of the inner or plain rollers 58 are journaled in blocks 60, adapted to slide in slots 61, produced in said plates. Springs 62 bear against the blocks 60 and the inner ends of the slots 61, which springs may be placed under tension or relieved from tension through the medium of set-screws 63. (Likewise shown in Fig. 4.) These springs 62 serve to keep the plain rollers of the pairs

in engagement with the corrugated or ribbed rollers, as is also shown in Fig. 4. The outer or corrugated husking-rollers 57 serve to drive the plain rollers, and the corrugated husking-rollers 57 are driven through the medium of bevel-gears 64, secured to their upper trunnions and engaging with similar gears 65, secured to the end portions of the driven shaft 53.

Each pair of husking-rollers is located within a housing or casing 66, the housings or casings being open at both of their ends and having corresponding inclination to the inclination of the husking-rollers. The rear or larger ends of the husking-rollers are adjacent to a trough 67, supported, preferably, between the rear cross-bar 12^a and the intermediate cross-bar 13^a of the auxiliary frame A'. The ends and sides of the trough 67 incline downward toward the center, and at the center or lowest point of the trough 67 an opening 68 is made. Below these openings a shaft 69 is journaled in suitable bearings attached to the auxiliary frame A', as is illustrated in Fig. 2, the shaft 69 extending longitudinally of the auxiliary frame. This shaft 69 carries a sprocket-wheel 70 and a bevel-gear 71, the bevel-gear 71 being arranged to mesh with a like gear 72, secured upon the end of a short shaft journaled transversely in the auxiliary frame A', and said short shaft carries a sprocket-wheel 73, (shown best in Fig. 2,) which sprocket-wheel 73 receives a chain belt 74. This chain belt extends upward and forward and passes over a sprocket-wheel 75, which is located on the driven shaft 53.

An elevator-frame 76 is mounted at its lower end at the lower portion of the trough 67, and this elevator-frame carries a sprocket-wheel at its upper end. An elevator-belt 77 is passed over the upper sprocket-wheel in the elevator-frame and over the sprocket-wheel 70 on the shaft 69, so that the ears of corn delivered into the trough 67 by the husking-rollers are carried up in the elevator by the belt 77, which is provided with flights 78, and as the elevator-frame inclines to one side of the machine and extends beyond said side the cleaned ears of corn are delivered by the elevator into a wagon or other receptacle at the side of the machine and traveling with it.

In order that the husks may be quickly removed from the ears of corn by the husking-rollers, downwardly and rearwardly extending arms 79 are secured at their upper ends to the rear ends 20 of the housings or casings 18 for the snapping-rollers, as is shown in Fig. 2. Each arm 79 carries at its lower rear end a roller 80, and each roller is provided with a circular knife 81. These knife-carrying rollers are located over the delivery ends of the conveyer belts or chains 45, and as the ears of corn snapped from the stalk drop from the conveyers 45 to the snapping-rollers C the knives 81 slit the husks of the

ears, but do not injure the grain. The knife-carrying arms 79 are of spring material, and the knives are held as near as practicable to the delivery ends of the conveyers 45 by 70 springs 82, attached to the rear ends of the housings for the snapping-rollers, the free ends of the springs having bearing on the arms 79 at a point near the knife-carrying rollers 80, as is shown in Fig. 2.

The ears of corn, with their husks slit, drop upon the husking-rollers C, and as each set of husking-rollers run close together, they quickly pinch the slit husks and strip them from the ears of corn. As the husked ears 8c of corn travel down the husking-rollers to the elevator any silk still adhering to the ears or any ribbons of husks still remaining on the corn will be removed by the husking-rollers, so that the ears of corn will be delivered in a clean condition to the elevator. One husking-roller being rough or corrugated and the other plain the ears of corn received by the husking-rollers will be caused to turn around as they travel along the rollers, thus facilitating the removal of any material left clinging thereto after the first husking operation has been accomplished.

The auxiliary frame A' is raised and lowered through the medium of a lever 83, fulcrumed upon a standard 84, carried by the main frame A, as is shown in Fig. 1. The forward end of this lever 83 is adjustably attached to a link 85, pivotally connected with the rear central portion of the auxiliary frame A', while the rear or handle end of the lever 83 is provided with a thumb-latch 86, adapted to enter any one of a series of apertures 87, produced in a standard 88, located on the main frame A, as is also shown best in Fig. 1. The draft-tree 89 is attached to the main frame, preferably in advance of the perforated keeper-standard 88.

In the operation of this machine it will be observed that the stalks of corn are guided between the snapping-rollers. The ears of corn are then snapped from the stalks by said snapping-rollers and passed to the conveyers 45, and the husks of corn as the ears leave the conveyers are slit by the knives 81. The ears of corn with their husks thus slit are dropped upon the husking-rollers, which immediately act to strip the major portions of the husks from the ears, while any remaining shreds of husks or of silk are removed from the ears by the husking-rollers as the ears travel down the said rollers. The husking-rollers deliver the cleaned or husked ears of corn to the trough 67, whereupon the elevator acts to carry up said ears of corn 125 and deliver them to a receptacle prepared to receive them.

I desire it to be understood that the drive-chain 38 and connecting-wheels may be omitted from one side of the machine, if desired, 130 and that the usual ratchet mechanism may be added to the drive-wheels, which will en-

able one wheel in turning to go ahead, while the other simply turns as on a pivot.

Having thus described my invention, I claim as new and desire to secure by Letters

5 Patent—

1. In a corn-harvester, a wheel-supported frame, snapping-rollers mounted in the frame to revolve in opposite directions, a housing for each snapping-roller, a trough within each 10 housing parallel with the outer sides of the snapping-rollers, and endless conveyers mounted to travel in each trough, arms supported opposite the rear end of each trough, and disk cutters mounted to revolve on said 15 arms, adapted to slit the husks of corn as the ears drop from the conveyer, and thus prepare the ears for ready husking, as described.
2. In a corn-harvester, the combination with a wheel-supported frame, snapping-rollers 20 mounted to revolve in the frame, housings for the snapping-rollers, guide-fingers extending from the forward ends of the housings, troughs in the said housings parallel with the outer side faces of the snapping-rollers, and 25 endless conveyers mounted to travel in the troughs, of arms secured opposite the outlet ends of the troughs, disk cutters carried by said arms and located in the path of the ears discharged by the conveyers, husking-rollers 30 arranged in pairs, one pair at the rear of and below the outlet end of each conveyer-trough, the husking-rollers receiving ears for contact 35 with the slitting-disks, a trough arranged to receive the ears of corn from the husking-rollers, and an elevator in connection with the receiving-trough, all combined for the purpose set forth.
3. In a corn-harvester, the combination, with a wheel-supported main frame, an auxiliary 40 frame pivotally carried by the main frame, and means for raising and lowering the said auxiliary frame at its rear portion, of housings located at the forward portion of the auxiliary frame and supported thereby, 45 the housings being open at their opposing longitudinal faces and provided with guide-fingers at their forward ends, snapping-rollers mounted to revolve in the said housings, the snapping-rollers being provided with longitudinal 50 teeth or ribs, means for driving the said rollers in opposite directions, conveyers

located also within the housings or casings at the outer side portions of the snapping-rollers, a driving mechanism for the said conveyers, husking-rollers arranged in pairs, also 55 mounted in the auxiliary frame and arranged to receive the ears delivered by the conveyers, a driving mechanism for the said husking-rollers, and an elevator carried also by the auxiliary frame and adapted to receive 60 the cleaned ears from the husking-rollers, as set forth.

4. In a corn-harvester, the combination, with a wheel-supported main frame, an auxiliary frame pivotally mounted in the main 65 frame, means for raising and lowering the rear portion of the auxiliary frame, housings or casings having a forward and downward inclination, their opposing inner longitudinal surfaces being open, guide-fingers carried 70 by the forward ends of the said casings, and conveyer-chains for the stalks mounted upon the housings or casings adjacent to their inner longitudinal edges, of snapping-rollers, mounted in the housings or casings, means 75 for revolving said snapping-rollers in opposite directions, each snapping-roller being of greater diameter at its rear than at its forward end and provided with longitudinal peripheral teeth or ribs, conveyers located also 80 within the housings or casings adjacent to the outer side faces of the snapping-rollers, tension-controlled knives supported over the delivery ends of the conveyers, husking-rollers arranged in pairs having a downward and 85 rearward inclination, each pair of husking-rollers having their rear ends of greater diameter than their forward ends, one roller of each pair being plain and the other roughened, tension devices for the husking-rollers, 90 means for driving the said husking-rollers, an elevator arranged to receive the ears of corn from the husking-rollers, and means, substantially as described, for driving said elevator, for the purpose specified. 95

In testimony whereof I have signed my name to this specification in the presence of two subscribing witnesses.

JOHN STRAND.
